UNITED STATES PATENT OFFICE.

GEORGE A. SEIB, OF ILION, NEW YORK, ASSIGNOR TO REMINGTON TYPEWRITER COMPANY, OF ILION, NEW YORK, A CORPORATION OF NEW YORK.

TYPEWRITING-MACHINE.

1,378,486.

Specification of Letters Patent. Patented May 17, 1921.

Application filed September 18, 1916. Serial No. 120,853.

To all whom it may concern:

Be it known that I, GEORGE A. SEIB, citizen of the United States, and resident of Ilion, in the county of Herkimer and State of New York, have invented certain new and useful Improvements in Typewriting-Machines, of which the following is a specification.

Broadly stated my present invention relates to locking devices for screws or bolts and its general object is to provide improved devices of the character specified. The improved screw locking devices, however, were especially designed for use in typewriting machines in connection with the adjustable screws that regulate the tension of the compression or restoring springs for the key levers, and the particular object of the invention is to provide comparatively simple and inexpensive but effective devices for affording individual adjustment and setting or locking of the said screws which are in effect abutments with which the ends of the compression springs co-operate. Another object of the invention is to provide an improved method of manufacturing screw locking or holding devices.

To the above and other ends my present invention consists in the features of construction, combinations of devices and arrangements of parts hereinafter described and particularly pointed out in the claims.

In the accompanying drawing,

Figure 1 is a fragmentary front to rear vertical sectional view of the lower portion of a front-strike Remington typewriting machine to which the preferred form of my invention is shown as applied.

Fig. 2 is a fragmentary bottom plan view of my improved screw locking devices.

Fig. 3 is an enlarged transverse sectional view taken on a plane indicated by the dotted line $\alpha\alpha$ in Fig. 2.

Fig. 4 is a view corresponding to Fig. 3 but showing a preliminary stage in the method of carrying out my invention.

As appears from Fig. 1, the base 1 of the main frame of the said Remington typewriting machine has arranged within it a set of key levers 2 which are fulcrumed at 3 in the rear of the base, the key levers each being provided with a key cap or button 4, and being connected in the ordinary way by devices comprising links 5 with the

usual printing instrumentalities which are not herein disclosed. As is usual, each key lever is provided with an individual restoring spring which assists to restore it and the connected parts to normal position after operation. In the present instance the restoring springs 6 (Figs. 1 and 2) are coiled compression springs vertically arranged below the key levers, the upper end of each spring fitting loosely around the lug or tooth 7 projecting downward from the key lever slightly forward of its fulcrum. The lower portion of the spring is housed in a tapped hole or opening indicated at 8 in a cross bar 9 suitably secured in the sides 60 of the base, and the bottom end of the spring rests on and cooperates with an adjustable abutment in the form of a threaded member or headless screw 10 that is threaded into the hole 8 from the bottom. 65

It will be understood that the tension or pressure exerted by the spring 6 on its key lever 2 may be varied and regulated by adjusting the screw 10 in the bar 9 and that in order that the action of the spring after 70 such adjustment may be constant it is necessary to set, fix or lock the screw 10. My present invention is more especially concerned with improved locking or holding means for this purpose, which means is at 75 once simple and highly efficient.

The preferred method of carrying out my invention will now be described. It will be noted that the bar 9 in which the screws 10 are mounted is provided at its under side 90 with a shoulder 9^a that separates the front portion from the narrower rear portion of the bar. This bar, as has been stated, is detachably secured in the base. The securing may be done by pairs of screws 9^b at the 95 sides of the base, the end portions of the bar being provided with upwardly extending flanges, each flange receiving the upper one of the associate pair of screws 9^b. Prior to being mounted in the base the bar 100 is turned over so that its bottom side is uppermost. A thin metallic fillet or filling strip 11 (Fig. 4) is then arranged on its rear portion back of the shoulder and over this is placed a somewhat thicker locking 105 strip 12 which, as appears most clearly in Fig. 2, is divided by a series of transverse kerfs or cuts 13 into a set of parallel tongues 14. These tongues correspond in number 110 to the number of key levers and key lever

restoring springs and are joined by the uncut connecting portion 15 of the strip or bar 12. This bar is of steel and the tongues 14 are resilient. The bar 12 and the filling strip 11 are securely fixed to the bar 9 back of the shoulder 9^a by means of headed screws 16 which are threaded into openings in the bar 9 that preferably extend through the thickness of the bar. There are a sufficient number of these screws 16 to securely hold the bar 12 and the filling strip 11 in place. Thus secured, the holes 8 are drilled and tapped, the holes passing not only through the bar 9 but through the tongues 14 and the filling strip 11. The tapping is done first through the tongues 14, next through the filling strip, and then through the body of the bar 9. The thickness of the filling strip may vary but care must be taken that in no case shall it be equal in thickness to the pitch of the screw 10. Preferably the thickness of the filling strip corresponds to about half of the pitch of the screw 10 and consequently of the tap employed. The operations described having been performed, the screws 16 are unscrewed and the filling strip 11 removed, whereupon the screws 16 are screwed in again, thus securely fixing the tongued strip 12 directly to the supporting bar 9. When so secured the tongued strip 12 lies flat against the bar 9 back of the shoulder so that the threaded hole 8 is continuous, but it will be understood that the threads in the parts 12 and 9 are not continuous, owing to the removal of the filling strip, the thickness whereof, as has been stated, is preferably equal to about half the pitch of the threads in the hole 8. For convenience of description, that portion of the hole 8 that is in the tongue 14 of the strip 12 will be designated as 8^a. Normally the axes of the threaded holes 8 and 8^a will coincide with each other. The result of the construction and arrangement will be that if now a screw 10 be inserted in the hole 8^a and screwed in, the relationship between the tongue 14 and the bar 9 will not be affected at first. When, however, the inner end of the screw reaches the bar 9 it will not immediately enter the hole 8 since the continuity of the threads has been interrupted, and it must be turned some distance (half a turn, for example) before it can properly engage with the thread in the hole 8. During this rotary movement of the screw 10 it will not advance longitudinally and consequently the tongue 14 (as shown in Fig. 3) will be forced away from the face of the bar 9 against which it is secured a distance about equal to the thickness of the fillet, the resilient quality of the tongue enabling it to bend from its root where it joins the connecting base or body 15 of the bar 12. This bending or yielding movement of the tongue 14 will continue until the screw 10

engages with the threads in the hole 8, thus enabling the inward longitudinal movement of the screw to be resumed. It will be understood that the bending movement of the resilient tongue 14 corresponds about to the thickness of the fillet 11 and also that as a result of this bending or yielding movement of the tongue it will grip the screw, exerting a locking or restrictive action on it so as to prevent accidental turning or displacement of the screw after it has been once properly adjusted or set. At this time the axes of the holes 8 and 8^a will be at an angle one to the other. It will therefore be understood that the action of one of the screws 10 on its associate tongue 14 does not affect any other tongue. In other words, the series of tongues, though forming part of a single part or piece 12, operate independently of each other and afford individual adjustment and setting of their associate screws so that the single piece 12 enables me in effect to obtain the results which would have to be obtained otherwise by the employment of separate washers or nuts, corresponding in number to the tongues formed in the strip 12. It will also be observed that the location of the bar 9 in the machine is such that after it has once been secured in place the screws 10 may readily be adjusted after the key actions have been assembled and the springs 6 arranged in the holes 8 and in contact with the screws 10, the assembler being able to test the individual type actions with one hand while controlling the screw adjustment by a screw driver in the other hand. It will be observed that by my present invention there is provided a plurality of threaded members, in the present instance headless screws or bolts, which form bottom pieces or closures for the seats or housings of the set of springs, the springs in the present instance being connected to the key levers of the typewriting machine and operating to restore said key levers after actuation; that combined with these screws or members is a single device for locking said screws or members in set positions while affording individual adjustments thereof whereby the tension of the springs may be controlled and varied; that the locking device in the present instance comprises a bar provided with a plurality of individual resilient, yieldable or spring tongues arranged parallel with each other and having tapped openings through which the screws or tension controlling members are threaded before said members enter the threaded openings in the supporting bar; that as a result of breaking the continuity of the threads in the tongues and the supporting bar, the tongues and the supporting bar are relatively yieldable through the action of the threaded members or screws, the effect being to lock the screws against accidental turning movement

while affording individual adjustment of said screws; that the method of providing for locking a threaded member or a series of threaded members in its or their support 5 consists in securing to said support in the first place a fillet strip and a locking strip, the fillet strip being interposed between the locking strip and the support, then drilling and tapping a hole through the three parts, 10 then in removing the fillet strip and re-securing the locking screw to the support; that the thickness of the fillet strip must not correspond to the pitch of the threads since it is desired to interrupt or break the continuity 15 of the threads by removing the fillet strip; that the axes of the threaded opening in the tongue and of the corresponding opening in the support or bar are normally coincident; that the effect of threading the member or screw into the tongue is to cause said screw to operate automatically as it is turned to change the relationship of said axes, the axis of the hole in the tongue being thrown out so that it is at an angle to the axis of 20 the hole or threaded opening in the support or bar; and that as a result of my invention I have provided an efficient and simple means for locking a plurality of threaded members or bolts on a common support without interfering with their separate adjustability and also a simplified method by which 25 this resulting means is produced.

While my invention has been designed primarily for use in typewriting machines 30 and the preferred form of it is embodied in such a machine, nevertheless applications of it to other machines and in other forms will readily suggest themselves, and it will of course be understood that various constructional changes may be made without departing 35 from my said invention.

What I claim as new and desire to secure by Letters Patent, is:

1. The combination with a plurality of 40 threaded members and a support therefor, of a single device for locking said members in set positions while affording individual adjustments of said members to any desired extent without at the same time disturbing the locking engagement of said device with 45 the remaining threaded members, and means for securing said locking device; the aforesaid individual adjustments of said threaded members being also accomplishable without disturbing said securing means.

2. The combination with a plurality of 50 springs, a plurality of adjustable tension controlling members, one for each spring, and a support for said members, of a single device for locking said members against accidental displacement while affording individual adjustments of said members to any desired extent.

3. The combination of a set of key controlled elements, springs connected with said

elements, members one for each spring for varying the effect of said springs, a support for said members, and a single device for holding said members in set positions, said members being individually adjustable to any desired extent to vary said set positions.

4. The combination of a set of key levers, coiled springs connected with said key levers, adjustable abutments co-operative with said springs, a support for said abutments, and a single device for holding said abutments in adjusted positions, said abutments being each individually adjustable while said device is effective on the others.

5. In a typewriting machine, the combination of a set of key levers, coiled restoring springs connected to said key levers, a bar containing holes in which said springs are partly housed, screws threaded into said holes and co-operative with said springs to afford compression thereof and to vary such compression, and a locking bar provided with individual spring tongues through which said screws are also threaded, said tongues co-operating with said screws to hold them in adjusted positions.

6. The combination of a plurality of threaded members, a supporting bar in which said threaded members are disposed, and a locking bar secured to said first recited bar and provided with individual tongues co-operating with said threaded members.

7. The combination of a support containing a threaded opening, a resilient part containing a threaded opening in register with the threaded opening in said support so that the axes of the two threaded openings are normally coincident, the continuity of the threads, however, in the two threaded openings being interrupted, and a threaded member that is received in both said support and said resilient part, the turning of said threaded member being effective automatically to change the relationship of said axes so that they are angularly disposed.

8. The combination of a support containing a series of threaded openings, threaded members engaging in said openings, and a locking bar provided with a series of resilient tongues, each tongue formed with a threaded opening in which one of said threaded members engages.

9. The combination of a support containing a series of threaded openings, screws engaging in said openings, and a locking bar provided with a series of parallel independently yieldable tongues, each tongue formed with a threaded opening in which one of said screws engages.

10. The combination of a support containing a series of threaded openings, threaded members engaging in said openings, and a series of parallel independently yieldable

tongues, each tongue formed with a threaded opening in register with one of the threaded openings in said support, the continuity of the threads, however, in each pair of registering threaded openings being interrupted, each threaded member also engaging in one of said tongues.

11. The combination of a threaded member, a support into which said member is 10 threaded, and a resilient tongue in which said member is also threaded, the axes of the threaded opening in said support and the threaded opening in said tongue being normally coincident and the threads in 15 said parts being discontinuous; the effect of threading the member into the tongue and thence into the support being to alter automatically as said member is turned the relationship between the tongue and the 20 support and also to alter the relationship of the axes of said threaded openings.

12. Means for locking a threaded member in set positions comprising two relatively yieldable parts each provided with a threaded opening for receiving said member, the threaded openings being in register but the threads in said openings being discontinuous, said member operating when turned to automatically throw the axes of said threaded 30 openings out of register.

13. The method of providing for locking a threaded member in its support which consists in securing to said support a fillet or strip and a locking strip, the fillet being 35 interposed between the locking strip and the support, then drilling a continuous hole through the three parts, then tapping the hole, then in removing the fillet and re-securing the locking strip to the support.

40 14. The method of providing for locking a threaded member in its support which consists in securing to said support a filling strip and a locking strip, the filling strip being interposed between the locking strip 45 and the support, then drilling and tapping a hole through the three parts, then in removing the filling strip and re-securing the locking strip to the support, the filling strip having a thickness less than the pitch of the 50 threads of the tap.

15. The method of providing for locking a series of independently adjustable threaded members in their support which consists

in securing to said support a fillet and a locking strip, the locking strip being formed 55 with a series of parallel tongues, the fillet being interposed between the locking strip and the support, then drilling and tapping a series of holes, each hole passing through one of said tongues and through the fillet 60 and then into the support, then removing the fillet and re-securing the locking strip to the support with one of the tapped openings in each tongue in register with one of the tapped openings in the support. 65

16. The method of providing for locking a series of independently adjustable threaded members in their support which consists in first securing to said support a locking strip and an interposed fillet, the locking 70 strip being formed with a series of parallel tongues, then drilling and tapping a series of holes, each hole passing through one of said tongues and through the fillet and then into the support, and then in removing the 75 fillet and re-securing the locking strip to the support with one of the tapped openings in each tongue in register with one of the tapped openings in the support, the thickness of the fillet preferably corresponding 80 to about half the pitch of the thread with which it is tapped.

17. The method of providing for locking a threaded member in its support which consists in first securing to said support a locking strip and an interposed filling strip, then drilling and tapping a hole through the two strips and the support, and finally in removing the filling strip and re-securing the locking strip, the filling strip having a thickness 85 differing from the pitch of the threads of the tap. 90

18. In a typewriter, pivoted key levers, tension springs and adjusting screws therefor, and a plate with a plurality of spring 95 tongues, one for engaging each of the adjusting screws, to hold said screws in any rotatable position.

Signed at Ilion, in the county of Herkimer and State of New York, this 15th day of 100 September, A. D. 1916.

GEORGE A. SEIB.
